ATTORNEY

UNITED STATES PATENT OFFICE.

ANTHONY T. CENTANNI, OF PHILADELPHIA, PENNSYLVANIA.

NAIL-FILE ATTACHMENT.

Application filed July 8, 1927. Serial No. 204,368.

The present invention relates to an improved attachment for nail files, the purpose being to provide such a device as will permit the file to be carried in one's pocket and not to drop out in case the person leans over.

Another purpose is to provide a nail file attachment, wherein the attachment comprises a clip including a tongue for engaging the wall of the pocket, and bent over lugs for the purpose of engaging opposite notches formed in the edges of the file, the tongue lying flat against one face of the file so as to engage on the outside of the wall of the pocket, with the file inside the pocket, the lugs acting to keep the attachment securely fastened to the file.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view in perspective of the improved attachment consisting of a clip as applied to a finger nail file.

Figure 2 is a similar view showing the opposite face of the file.

Figure 3 is an enlarged detailed view of the clip detached from the file.

Figure 4 is a sectional view on line 4—4 of Figure 2.

Referring to the drawings, 1 identifies a finger nail file, the opposite edges of which are provided with notches 2, which are engaged by lugs 3 formed integrally with an attachment such as a clip 4. The lugs are bent around the edges in engaging with the notches, and the clip is of elongated form and has an outwardly bent portion 5 which merges into a tongue 6 which is located adjacent the face of the file and the outer wall of the pocket will engage between the clip 4 and the file. The clip has an extension 7

which bears against the face of the file adjacent its rounded edge, so as to bear against the face of the file and create tension for the clip when it is sprung laterally from the face of the file to permit the outer wall 55 of the pocket to engage between the file and the clip. The extremities of the lugs are counter-sunk in depressions 9 in one face of the file so as to act additionally to prevent displacement of the attachment and at 60 the same time avoid any obstructions in the act of inserting the file in one's pocket.

The invention having been set forth what is claimed is:

1. The combination with a finger nail file 65 having notches in its opposite edges of an attachment comprising a clip stamped from one piece of spring sheet metal having an elongated tongue to bear on the outside of the wall of the pocket with the wall of the 70 pocket between the tongue and the file, said clip having opposite lugs bent around the file and in engagement with the notches to prevent displacement of the clip, said clip having an extension beyond the tongue bearing 75 against one face of the file to secure tension sufficient to cause the clip to properly engage with the outer wall of the pocket.

2. The combination with a finger nail file having notches in its opposite edges of an 80 attachment comprising a clip stamped from one piece of spring sheet metal having an elongated tongue to bear on the outside of the wall of the pocket with the wall of the 85 pocket between the tongue and the file, said clip having opposite lugs bent around the file and in engagement with the notches to prevent displacement of the clip, said clip having an extension beyond the tongue bearing 90 against one face of the file to secure tension sufficient to cause the clip to properly engage with the outer wall of the pocket, one face of the file having depressions in which the extremities of the lugs engage thereby further insuring securement of the 95 clip to the file.

In testimony whereof he affixes his signature.

ANTHONY THOMAS CENTANNI,
